UNITED STATES PATENT OFFICE.

SOMMERS CROWELL, OF PHILADELPHIA, PENNSYLVANIA.

FENCE-GUARD.

SPECIFICATION forming part of Letters Patent No. 573,571, dated December 22, 1896.

Application filed September 29, 1896. Serial No. 607,321. (No model.)

To all whom it may concern:

Be it known that I, SOMMERS CROWELL, a citizen of the United States, residing at Philadelphia, in the county of Philadelphia and 5 State of Pennsylvania, have invented a certain new and useful Improvement in Guards for Fences, of which the following is a specification.

The invention relates to a device for 10 mounting a garden-fence and supplemental therewith which has for its object the purpose of excluding predatory animals from an enclosure; and it consists of a series of metallic straps so bent longitudinally as to have 15 their base portions resting upon the upper surface of the cap of a fence and secured thereon by means of an overlying strip, which when bolted or screwed down maintains the device in its vertical position, the sides of 20 the straps from the base being bent so as to extend upward for attachment to a horizontal bar, and again bent over at their upper end to project downward at an acute angle outwardly from the vertical portions, and bevelled upon their sides a short distance from 25 their extremities to form sharp points thereon. In addition to the above-mentioned straps a series of intermediate spear-pointed short straps are projected from said horizontal bar, 30 extending above the vertical straps secured to the cap of the fence, as will be more fully understood from the following detailed description and accompanying sheet of drawings, in which—

35 Figure 1 represents a side elevation of a portion of a panel of a fence. Fig. 2 is an edge view of one of the series of straps A, with the intermediates b, the fence D, cap C, and overlying strip E being represented as 40 in section. Fig. 3 represents a plan view of the device, illustrating the method of joining two panels of a fence when arranged at right angles with each other.

Like letters of reference in all the figures 45 indicate the same parts.

In Figs. 1 and 3 of the drawings are represented a portion of a panel of a fence in which the series of straps A are formed of metallic bars so bent as to have the horizon-

tal base portion a made to conform in shape 50 but slightly less in width than the cap-piece C of the fence, (shown clearly in Fig. 2 of the drawings,) or it may be placed on the upper board and the cap-piece placed between the upright portions of the straps, occupying the 55 same position as the strip E, and secured in the same manner as represented by the series of screws b, one of which is shown in said figure, said screws being arranged at intervals along the line of the panel, thereby 60 binding the straps rigidly to the fence.

For greater security the rail G is placed between the upright portions of the legs, to which the latter are secured by means of bolts d. 65

The ends of the straps A are bent from the upper portion and made to project down and outwardly from the uprights at any desired angle as may be determined suitable, and bevelled upon their sides at the extremities to 70 form sharp points thereon for the purpose of preventing the passage beneath them of predatory animals.

Projecting upward from the sides of the rail G, and to which they are fastened by 75 means of the series of bolts d', are the short straps A', which are bevelled upon their extremities in the same manner as the free ends of the straps A. (Shown clearly in Fig. 2 of the drawings.) 80

I claim as my invention—

The fence-guard consisting of the straps A, having the horizontal base portion a, resting upon the fence, and attached upon the fence by the strip E, screwed upon the cap C, 85 the upper portions of the straps being bent down and outwardly from the upright at any angle therefrom, the rail G with the series of intermediate straps A', projecting above the rail G, the extremities of the two series of 90 straps being bevelled upon their sides and terminating in points, in combination with the upper edge of a fence, substantially as shown and described.

SOMMERS CROWELL.
